UNITED STATES PATENT OFFICE.

FLOYD S. HOXSIE, OF BARSTOW, CALIFORNIA.

DESIGN FOR AN INCENSE BURNER.

Application filed December 7, 1926. Serial No. 19,959. Term of patent 7 years.

To all whom it may concern:

Be it known that I, FLOYD S. HOXSIE, a citizen of the United States, residing at Barstow, in the county of San Bernardino and State of California, have invented a new, original, and ornamental Design for Incense Burners, of which the following is a specification, reference being had to the accompanying drawing, forming part thereof.

The figure is a perspective view of an incense burner, showing my new design.

I claim:

The ornamental design for an incense burner, substantially as shown.

In testimony, that I claim the foregoing as my own, I have hereto affixed my signature.

FLOYD S. HOXSIE.
